TIMING DEVICE FOR WASHING MACHINES

Gustav B. Keil, St. Joseph, Mich., assignor to
 Nineteen Hundred Corporation, Binghamton,
 N. Y., a corporation of New York

Application January 17, 1931, Serial No. 509,395

2 Claims. (Cl. 161—1)

This invention relates to improvements in washing machines of the electrically operated type and more particularly has reference to timing mechanism associated with such machines for regulating the duration of operation of the same.

It is frequently desirable in the use of washing machines of the type commonly employed in the washing of clothes to provide for a predetermined period of operation of the machine which under normal circumstances has been found sufficient to produce the desired results. At the same time the control over the operation of the machine should be flexible so as to permit of operations of variable duration depending upon the nature and quantity of the articles being washed. One batch of clothes may be properly handled by the machine in a period of say five minutes while other batches of clothes may require ten or fifteen minutes operation of the machine to effect the desired cleansing action.

A primary object of the present invention has been to provide a simple and effective automatic control mechanism which may be adjusted to predetermine periods of operation, of variable duration. By the provision of the means contemplated it is possible to set the machine into operation and then leave it after suitable adjustment of the control mechanism. At the end of the selected period of operation the machine will be automatically shut off and the operator may return at any time to remove the contents of the tub. The devices which the invention has in view are not only simple of construction and easy to adjust but they are readily applicable to washing machines of the types now being commercially produced.

Other objects and advantages of the invention will appear from the detailed description of an illustrative embodiment of the same which will now be given in conjunction with the accompanying drawings in which:

Figure 1 is an elevational view partly in section disclosing the principal portions of the timing device.

Figure 2 is a horizontal, sectional view through the timing mechanism taken along the broken line 2—2 of Figure 1.

Figure 3 is an end view of the controlling switch and shows diagrammatic connections to the driving mechanism of the machine.

Figure 4 is a detail view in section taken along the line 4—4 of Figure 1, and

Figure 5 is a sectional detail view taken along the line 5—5 of Figure 1.

Referring now to the drawings, the washing machine to which the control mechanism of the present invention is applied may be of any conventional form and may, for example, include an outer casing 10 surrounding an inner tub element 11. Between the tub and the outer casing there may be provided a vertically extending shaft 12 which at its lower end is connected in the usual way to the operating mechanism of the machine and at its upper end is adapted to be connected to the wringer mechanism. A separate frame or plate 13, on which is mounted the major portion of the control mechanism, may be suitably mounted between the casing 10 and the tub 11 as by securing the same, by means of screws 14, to a separate casting 15 which is attached by screws 16 to the outer casing 10. The casting 15, as shown, may suitably be provided with an opening through which the shaft 12 extends.

Near the bottom of the frame 13 there may be provided a horizontal extension forming a suitable bearing 17 adapted to support a shaft 18. At the right end of the shaft there may be secured a toothed wheel or pinion 19 which is adapted to cooperate with a tooth or projection 20 carried by a collar 21 secured to the shaft 12 in a suitable position by means of a set-screw 22.

At its opposite end the shaft 18 may be provided with a collar 23 which is secured to the shaft by means of a set-screw 24 and carries a spring-pressed ball 25, extending from its inner face. This ball is adapted to cooperate with any one of a series of depressions 26 formed in a collar 27 secured to an extension of the bearing 17. The depressions 26 are equal in number to the teeth carried by the wheel 19 and are so located that upon turning of the wheel a single tooth space, the ball 25 will be carried from one depression to the next. It will be clear that upon each revolution of the shaft 12 the projection 20 will engage a tooth of the wheel 19 and rotate the latter through the distance of a single tooth space and will cause the ball detent to shift in the manner indicated from one depression to the next. The detent will serve to prevent any overthrow of the wheel 19 and shaft 18.

At an intermediate point of the shaft 18 there is provided a worm 28 adapted to cooperate with a worm wheel 29 keyed or otherwise secured to a sleeve 30. This sleeve, as shown in Figure 2, is loosely mounted upon a stud 31 carried by the frame 13. A knob 32 is formed at the forward end of the sleeve and a graduated dial 33 may

suitably be provided adjacent the knob. The face of the dial, which may, as shown, be arranged on a beveled surface, may be calibrated in any suitable way, preferably to designate minutes. The graduations on the dial may for this purpose be adapted to cooperate with a suitable index carried by an annular member 34 surrounding the dial and mounted in an opening in the outer casing.

10 At any suitable point, preferably on the inner face near its periphery, the worm wheel 29 may be provided with a pin or stud 35 which in the course of rotation of the worm wheel may be brought into cooperation with an arm 36 of a bell-crank lever pivoted on a stud 37 extending from the frame 13. The opposite arm of the lever may carry a contact element 38 adapted, in one position of the lever, to cooperate with a pair of spring contact elements 39 and 40 (Figure 3). 15 These elements may in turn be connected in series with any suitable source of current 41 and the motor 42 which serves to drive the machine.

20 As best shown in Figure 1, the arm 36 of the lever may be provided with a substantially right-angled bend and at the elbow thus formed there may be pivotally connected a pin 43 which is adapted to cooperate with an opening in a bracket 44 carried by the frame 13. A spring 45 surrounding the pin 43 and compressed between the 25 bracket 44 and a shoulder at the upper end of the pin serves to hold the lever in either the full line position shown in Figure 1 or in the dotted line position shown therein. It will be understood that in the movement of the lever from one position to the other it passes through a dead center position with reference to the spring 45 and as soon as it passes beyond this dead center it 30 will be thrown by the spring into the other extreme position.

35 40 Suitable manual means may be provided for rocking the lever to carry the contact element 38 into and out of cooperative relation with the contacts 39 and 40. For this purpose a finger-piece 46 may be pivotally mounted by means of a stud 45 or trunnions 47 carried by an extension of the frame 13. The inner end of the finger-piece or lever 46 may carry a pin 48 adapted to cooperate with an elongated slot 49 in the arm 36 of the lever. It will be clear from the construction 45 shown that as the exposed end of the finger-piece is depressed, the pin 48 will be lifted to rock the arm 36 in a counter-clockwise direction in Figure 1 and thus carry the contact 38 downwardly to close the switch. Movement of the 50 finger-piece in the opposite direction will correspondingly serve to open the switch.

55 To permit adjustment of the dial 33 and the pin 35 with reference to the driving worm 28 and the switch arm 36, the dial is adapted to be shifted outwardly along the supporting stud 31 to disconnect the worm wheel 29 from the worm 28. To permit disengagement of the parts by the axial sliding of the worm wheel, the latter is formed with straight ended teeth, as shown 60 in Figure 2, rather than with teeth having curved ends. When the worm and worm wheel are disconnected in this way the dial and connected parts may be rotated to any desired position, placing the pin 35 in any selected relation to the 65 switch arm 36. When the dial pin has thus been properly set, the knob 32 may be pressed inwardly to again connect the worm and worm wheel.

70 A spring-pressed ball 50 carried by the sleeve 30 and the hub of the worm wheel 29 may co-

operate with either one of a pair of grooves 51 and 52 formed in the stud 31 to hold the worm wheel in either connected or disconnected position with relation to the worm.

5 A typical operation of the control mechanism may be as follows:

The knob 32 may first be pulled outwardly to disengage the worm and worm wheel and the knob may then be rotated until any desired graduation on the dial 33 is brought into line with the index 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290
